OIL CLARIFIER

George H. Amsden, Farmington, N. Mex.

Application February 24, 1941, Serial No. 380,333

1 Claim. (Cl. 210—185)

This invention relates to improvements in mechanism for clarifying liquids such as lubricating oil, cooking oil, cleaning solvents, gasoline, etc.

The primary object of this invention is the provision of an improved means for reclaiming engine lubricating oils and the like in an efficient, economical and expeditious manner.

A further object of this invention is the provision of an improved process for clarifying lubricating oils and the like.

Other objects and advantages of this invention will be apparent during the course of the following detailed description.

In the accompanying drawings, forming a part of this specification, and wherein similar reference characters designate the corresponding parts throughout the several views,

Figure 1 is a side elevation of the improved oil reclaiming apparatus.

Figure 2 is a vertical cross sectional view through the improved oil reclaimer; taken substantially on the line 2—2 of Figure 1.

Figure 2a is an enlarged fragmentary cross sectional view taken at the juncture of the top and bottom container portions of the improved apparatus.

Figure 3 is a top plan view of the improved apparatus.

Figure 4 is a plan view of the lower receptacle of the improved apparatus, showing the oil screening arrangement.

Figure 5 is a plan view of the screen used for the apparatus.

Figure 6 is a plan view of a gasket associated with the device.

Figure 7 is a plan view of the lower bulk head of the apparatus.

In the drawings, wherein for the purpose of illustration is shown only a preferred embodiment of the invention, the letter A may generally designate the improved oil reclaiming mechanism. It may include upper and lower receptacle portions B and C and a filtering and screening assemblage D located therebetween.

The upper container portion B includes a main body 10 of preferably cylindrical formation having a lower inturned flange 11 extending convergently downward and adapted to socket within the lid portion 12 of the bottom receptacle C, as shown in Figures 2 and 2a. Otherwise the entire bottom of the upper container B is open so that the oil to be reclaimed may have access to the filter and screening arrangement D.

The upper margin of the container body 10 is

provided with relatively spaced lugs 11a adapted to cooperate with the interrupted lug sockets 12a provided upon the rolled outer edge of the lid 13 of the upper container B in a manner which is perfectly apparent from Figures 1 and 2 of the drawings, so as to secure attachment or detachment of the lid with respect to the container.

The lid 13 is imperforate. It is provided with an air pressure gauge 14 of approved type, and furthermore it has a screw threaded man hole entrance 15 and a screw threaded cap 16 therefor. The cap 16 preferably supports an air valve 17 to which a suitable pump may be connected for pumping air into the container B.

The lower container C is of construction similar to the container B, including a cylindrical shaped body portion 20 having a bottom wall 21a connected therewith. The lid 12 of the bottom container C is provided with supporting lugs 21 which rest upon the roll top 22 of the body 20, so that the lid 12 may be lifted with facility from the container body 20.

Referring to the filtering and screening arrangement D, the lid 12 is provided with openings 30, preferably $\frac{1}{8}$ of an inch in diameter in an arrangement similar to that shown in Figure 4 of the drawings. Other openings 31, very close to the marginal portion of the lid 12 are provided at a location which lies outwardly beyond the extreme bottom edge 32 of the flange 11 of the upper receptacle, as shown in Figure 2a of the drawings.

A screen 40, of any desired mesh, is bolted as at 41 in a number of places upon the cover portion of the lid 12; the diameter of the screen 40 being such that its marginal edge terminates approximately $\frac{3}{4}$ of an inch from the margin of the lid 12, as shown in Figure 4 of the drawings. Filter cloth or paper 45 is disposed upon the top of the screen 40 and extends to the extreme edge of the lid, that is, to the rolled supporting portion 21. A gasket 47, of ring shaped formation, rests upon the outermost marginal portion of the filter cloth or screen, beyond the outer circumferential edge of the screen 40, and is adapted to receive the edge 32 of the lower flange 11 of receptacle B in clamping engagement therewith. It is to be noted that this edge 32 of the flange 11 lies inwardly of the drain openings 31, so that any lubricant which filters by capillary attraction along the filter cloth or paper 45 will drain through the ducts 31. This avoids any leakage at the connection of the upper and lower receptacles B and C.

Improved means is provided for clamping to-

gether the receptacles B and C, together with the filtering and screening arrangement D, in proper leakproof relation. This means includes an upper bulk head 50 adapted to rest upon the top lid 13, and a lower bulk head 51 adapted to engage against the bottom 21a of the lower receptacle C. Each of these bulk heads is provided with a central enlarged portion adapted to socket respectively in the upper and lower ends of the receptacles B and C and a reduced outwardly extending flange portion designated at 52. The corners of the flange portions 52 have suitable openings 53. These openings are adapted to receive clamping and connecting rods 54, in the arrangement shown in Figure 1. Preferably, the rods 54 each have lower headed ends 55 and upper nuts 56 threaded on the upper ends thereof. Adjustment of the nuts 56 clamp the bulk heads upon the receptacles. Of course, this clamping effect forces the edge 32 of the flange 11 against the gasket 47 and seals the connection of the upper and lower receptacles.

The lower receptacle C is provided with a screw threaded plug 60 provided with a pet cock 61 therein. A gauge rod 62 is detachably extended at 63 thru an upper opening in the receptacle C and can be readily removed from the container in order to determine to what extent the reclaimed oil has dropped into the lower receptacle C.

It is to be noted that the upper bulk head 50 is provided with suitable cutouts to receive the gauge 44 and the man hole cover and valve, as shown in Figures 2 and 3 of the drawings.

Referring to the improved method of reclaiming oil or like fluids, attention is called to the fact that the upper and lower receptacles B and C are preferably of the same volumetric capacity, that is, five gallons. The oil to be reclaimed is first thoroughly mixed with fuller's earth, preferably the kind presently sold under the name "Retrol." Four pounds of such earth is preferably admixed with five gallons of oil to be reclaimed. It is noted in this connection that the fuller's earth is not deposited in the upper receptacle B and the oil poured thereon. These ingredients are first mixed together so that the earth is intimately dispersed throughout the oil body. In actual practice, after the admixed oil and earth are poured into the receptacle B, it will take about twenty-four hours for the earth to settle by gravity from the oil onto the screening arrangement. "Retrol" contains certain adsorptive clays which have the property of absorbing or filtering out carbon, neutralizing acidic compounds, coagulating saponifiable compounds and restoring a desirable color to a used oil. Thus, the acid content of the oil is reduced, which is known in the art as "improving

the acid number" of the oil, or "improving the neutralization number" of the oil. In this respect "Retrol" is more efficient than ordinary earth and three or four times as effective. This 5 is a distinct advantage in that the cake formed by the earth, after it has settled, is of less thickness than when raw fuller's earth is used, so that the reclaiming filtering operation may proceed as rapidly as possible.

10 The layer of earth after settlement occupies about the same relative position shown at 70 in Figure 2 of the drawings. The filter press cake formed by the earth after settlement can readily be removed. It is noted that the earth only 15 settles into cake form after the particles of the earth have become thoroughly saturated with oil.

After the admixed granular Retrol and oil to be reclaimed are thoroughly mixed, they are deposited in the upper receptacle B, either through the man hole opening 15 or by removing the top lid structure of the container B. Thereafter, the entire device is assembled and air is introduced thru the valve 17 into the compartment 25 of the container B above the body of oil therein. The pressure is elevated to about two pounds superatmospheric; just sufficient to enhance the filter action.

The filter earth may be reused, although I prefer to use fresh earth for each new reclaiming operation.

Various changes in the shape, size and arrangement of parts may be made to the form of invention herein shown and described, without departing from the spirit of the invention or the scope of the claim.

I claim:

In an oil reclaiming device, the combination of upper and lower receptacle portions having 40 compartments therein, the upper receptacle portion resting upon the lower receptacle portion and having an inturned lower flange extending inwardly over the compartment of the lower receptacle portion and otherwise being entirely 45 open at the lower end thereof, a cover for the lower receptacle portion having perforations therein, some of which lie inside of the marginal edge of the inturned flange of the upper receptacle, and other perforations therein lying 50 outside of the marginal edge of the inturned flange of the upper receptacle, screening and filtering means upon said cover of the lower receptacle portion, a ring-shaped gasket supported by the cover portion of the lower receptacle 55 portion and in position to be engaged by the inturned flange of the upper receptacle portion, and means for clamping said receptacle portions together in the relation specified.

GEORGE H. AMSDEN.
